(57) **CLAIM**

The ornamental design for a tapered projection for radio frequency aperture as shown and described.

DESCRIPTION

FIG. 1. is a front view of a tapered plate forming a part of the tapered projection;

FIG. 2 is a perspective view of the tapered plate;

FIG. 3 is an upper perspective view of a dielectric structure of the tapered projection;

FIG. 4 is a lower perspective view of the dielectric structure;

FIG. 5 is a side perspective view of the tapered projection formed by combining tapered plates with the dielectric structure; and,

FIG. 6 is a lower perspective view of the tapered projection. The broken lines immediately adjacent to the claimed area depict boundaries of the claimed design or environmental structure, and form no part of the claimed design.

1 Claim, 2 Drawing Sheets
